UNITED STATES PATENT OFFICE.

FRED BROWN PFEIFFER, OF AKRON, OHIO.

PNEUMATIC TIRE.

1,426,005.

Specification of Letters Patent. Patented Aug. 15, 1922.

Application filed November 28, 1919. Serial No. 340,995.

To all whom it may concern:

Be it known that I, FRED B. PFEIFFER, a citizen of the United States, residing at Akron, in the county of Summit and State of Ohio, have invented a new and useful Pneumatic Tire, of which the following is a specification.

It is the object of this invention to provide a casing for a pneumatic tire, which will possess extreme flexibility, and, at the same time, be practically puncture proof.

The invention aims to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in transverse section, a device constructed in accordance with the invention; Figure 2 is a top plan showing a portion of one of the strips; Figure 3 is a fragmental plan showing a portion of another of the strips; Figure 4 is a fragmental plan, showing a modification; and Figure 5 is a sectional detail enlarged from Figure 1.

The numeral 1 denotes the casing of a vehicle tire. In the casing 1 are embedded flexible metal strips 2 and 3. The strip 2 has slits 4 extending diagonally of the strip. Slits 5 are fashioned in the strip 3 and extend diagonally thereof, the slits 4 and 5 of the respective strips being located at an angle to each other. At their ends, the slits 4 and 5 merge into enlargements 6 located adjacent to the edges of the strips 2 and 3. If desired, a layer of elastic material 7, which may be rubber cement or the like, is placed between the strips 2 and 3, the said material entering the slits 4 and 5 and the enlargements 6. In this connection it is to

be observed that the slits 4 and 5 may be of any desired width.

In case it is desired that the tire casing shall have extreme flexibility along its longitudinal edges, then, as shown in Figure 4, auxiliary slits 8 may extend into the strips from the longitudinal edges thereof, the said slits terminating relatively near to the longitudinal edges of the strips, and merging into enlargements 9. The enlargements 6 and 9 give added flexibility to the device.

It is obvious that a tire casing constructed in accordance with the invention as above described will possess resiliency and strength, and, at the same time, will be practically puncture proof.

Having thus described the invention, what is claimed is:—

1. In a device of the class described, a casing; and superposed metal strips embedded in the casing, each strip having diagonal slits, all of which are located entirely within the strip, the slits of one strip being disposed at an angle to the slits of an adjoining strip. 75

2. A device of the class described, constructed as set forth in claim 1, and further characterized by the provision of enlarged openings in the strips, within the contour thereof, and located adjacent to the longitudinal edges of the strips and at the ends of the slits. 80

3. As an article of manufacture, for use in reinforcing a tire casing, a metallic strip having parallel longitudinal edges, the strip being provided with opened parallel slots located entirely within the contour of the strip and disposed at an acute angle to the longitudinal axis of the strip, the ends of the slots being disposed closely adjacent to the longitudinal edges, of the strip. 85

In testimony that I claim the foregoing as my own, I have hereto affixed my signature in the presence of two witnesses.

FRED BROWN PFEIFFER.
